UNITED STATES PATENT OFFICE.

GUSTAV B. PETSCHE, OF YONKERS, NEW YORK.

ROTARY COMPRESSOR.

Application filed October 6, 1920. Serial No. 415,143.

To all whom it may concern:

Be it known that I, GUSTAV B. PETSCHE, a citizen of the United States of America, and resident of Yonkers, county of West-
5 chester, State of New York, have invented a certain new and useful Improvement in Ro-
tary Compressors, of which the following is a true and exact description, reference being had to the accompanying drawings, which
10 form a part thereof.

My invention relates to rotary compres-
sors of the type in which the rotary piston
consists of an eccentric ring having an ex-
tension which forms a partition between the
15 admission and discharge ports of the pump.
The object of my invention is to construct
pumps of this kind especially suitable to
act as compressors at high speed, the ter-
minal pressure of which gases is a large mul-
20 tiple of the initial pressure. In this case
the volume discharged is only a small frac-
tion of the initial volume and the period
during which the outlet is to be open is only
a small part of the compression cycle. These
25 conditions require a discharge valve which
opens and closes the port with great ra-
pidity and positively. Further objects of
my invention are to provide a positively
actuated valve operating in connection with
30 the admission port of the compressor and
to close such port during the period when
the piston is out of contact with the wall of the
cylinder at which time re-expansion of that
part of the compressed substance, retained
35 in the clearance space and not discharged,
takes place. These residual gases build up
a pressure in the cylinder and would escape
into the admission port if it is not closed and
thus involve a considerable loss in volu-
40 metric efficiency, a loss to which other rotary
compressors, not having such valves are sub-
ject. A still further object is to provide the
piston with an automatically operating valve
for the release of excess pressure such as is
45 apt to occur in a compressor in which con-
siderable oil is carried with the gas to be
compressed and where the discharge valve
is opened and closed positively and a further
object is to provide for the actuation of the
50 delivery valve from the driving shaft of the
pump by means which will not involve the
use of stuffing boxes.

The nature of my improvements will be
best understood as described in connection
55 with the drawings in which they are illus-
trated, and in which

Figure 1 is a side elevation of a pump pro-
vided with my improvements taken on the
section line 1—1 of Fig. 2.

Figure 2 is a sectional elevation on the 60
line 2—2 of Fig. 1.

Fig. 3 is a sectional detail, and

Figure 4 is a sectional elevation showing
the application of my invention to an alter-
native construction of the pump. 65

A, A', indicate the pump cylinders formed
in the single casting and provided with face
plates A² and A³. B indicates the cylind-
rical wall of the cylinder cut away at
B' and B². C, Figs. 1 and 2, is a cylind-
rical bearing centered at H. D is the
admission port formed, as shown, through
the wall of the cylindrical bearing C.
E is the delivery port on the opposite
70 side of the compressor. F is the driving
shaft of the pump to which is secured the
eccentrics indicated at F', F', on which are
located the eccentric ring pistons G having
extending from them the extensions indi-
75 cated at G' and extending like the piston
from side wall to side wall of the pump
chamber. I, I', is a rock lever pivoted at
H and extending from wall to wall of the
bearing or valve chamber C. On one side
80 this rock lever carries an admission valve M
and on the other side a sliding shoe J, both
fitting to the bored face of chamber C.
T indicates a port formed through the par-
tition G' and provided with a valve T'
85 spring seated and capable of opening under
a determined pressure. N indicates a cylind-
rical seat or bearing for a rotary valve
formed on the outer side of the port E and
on this bearing works the rotary valve P
90 having a portion of its face depressed as
indicated at P'. This valve is rotated by
the shaft O on which is secured the gear
wheel Q in engagement with a gear wheel
Q' on the shaft F. Q² indicates a tight casing
95 enclosing the gearing to prevent escape of
gases which casing should be well charged
100 with oil.

Referring to Figure 4, it will be observed
that the eccentric ring piston G is here
105 shown as provided with an extension S
forming the slide working in the swivel
block R, seated in a bearing CC. The ad-
mission port to the compressing cylinder
is here shown at S' as formed through the
slide S and opening into the compressing
110 cylinder at S², the port S² bearing such re-
lation to the wall of the swivel block R

that it will be closed during the period when the piston is out of contact with the walls B of the cylinder. In other respects the construction of Fig. 4 is substantially similar to that of Figs. 1 and 2.

In operation the piston rotates in the anti-clockwise direction indicated by the arrow in Fig. 1. The fluid to be compressed is drawn in through the port M and delivered through the port E which, however, remains closed by the rotary valve P until the fluid has been compressed to the desired point at which point the port P' in the valve P registers with the port E and permits the escape of the compressed fluid into the receiver. Obviously, the amount of compression given to the fluid by the compressor will depend upon the location and length of the port P'. The rotary valve or valves where compressors are used in pairs, as indicated in Fig. 2, is driven from the main shaft F through the gears Q, Q', and stuffing boxes are avoided by encasing the gears, as shown, and providing oil in the gear case. While for a very high ratio of compression a delivery valve rotating in one direction as shown is practically necessary, an oscillating rotary valve may obviously be used where the ratio of compression is not so large.

It is important that such compressed fluid as may remain in the compression side of the pump at the end of its compression stroke should not be permitted to escape back through the admission port and should be held in the cylinder of the pump in admixture with the fresh charge of fluid to be compressed. The loss of pressure in the way indicated is prevented by providing the admission port with a valve which will close it during the period when the piston

leaves contact with the walls of the pump cylinder. In the construction of Fig. 1 this function is performed by the valve M and in the construction of Fig. 4 the admission port S² is closed by the bearing face of the swivel block through which the slide moves.

While I have shown the valve P as actuated by gearing which rotates it in one direction only, it will be obvious that any actuating gears or devices which will move it to open and close the port at proper times will be in a broad sense the full equivalent for the illustrated construction.

Having now described my invention, what I claim as new and desire to secure by Letters Patent, is:

1. In a rotary compressor having a rotary eccentric ring piston provided with an extension forming a division between the admission and discharge sides of the cylinder, a discharge port leading from the cylinder, a port formed through the piston extension and a spring seated valve in said port adapted to open the port under excessive pressure.

2. In a rotary compressor having a rotary eccentric ring piston provided with an extension forming a division between the admission and discharge sides of the cylinder, a bearing in the form of a cylindrical segment, a rock lever pivoted at the center of the bearing, a shoe on one end of the rock lever and a sliding admission valve on the other end, said rock lever being operatively connected to the piston extension, a discharge port leading from the cylinder, a rotary valve for opening and closing the discharge port located at the outer end of said port, means operatively connecting said valve to the driving shaft of the compressor and a tight casing enclosing said means.

GUSTAV B. PETSCHE.
